United States Patent Office

Des. 178,910
Patented Oct. 2, 1956

178,910

COORDINATE TABLE UNIT FOR A MACHINE TOOL

Kurt Zwick, Munich, Germany

Application August 30, 1955, Serial No. 37,722

Term of patent 14 years

(Cl. D54—14)

Fig. 1

Fig. 2

Fig. 4

Fig. 3

Fig. 5

Fig. 6

Fig. 7

Fig. 8

Fig. 1 is a front view of a coordinate table unit for a machine tool, showing my new design;

Fig. 2 is a rear view thereof;

Fig. 3 is a top view thereof;

Fig. 4 is a perspective view showing the front and one side thereof;

Fig. 5 is a right side view thereof;

Fig. 6 is a similar view with the apron in a different position;

Fig. 7 is a left side perspective view of the table; and

Fig. 8 is a similar view with the apron in a different position.

I claim:

The ornamental design for a coordinate table unit for a machine tool, substantially as shown.

UNITED STATES PATENT OFFICE
CERTIFICATE OF CORRECTION

Design No. 178,910

October 2, 1956

Kurt Zwick

It is hereby certified that error appears in the above numbered patent requiring correction and that the said Letters Patent should read as corrected below.

The patent was erroneously issued to the inventor, "Kurt Zwick", whereas said patent should have been issued to -- Hans Deckel, of Munchen-Solln, Germany, and Friedrich Wilhelm Deckel, of Zug, Switzerland, as assignees of the entire interest therein --; in the heading to the printed specification, between lines 5 and 6 thereof, insert -- Claims priority, application Germany March 11, 1955 --.

Signed and sealed this 27th day of November 1956.

(SEAL)
